Inventor:

John L. Bernecker

United States Patent Office.

JOHN L. BERNECKER, OF SAINT LOUIS, MISSOURI.

Design No. 2,744, dated August 13, 1867.

DESIGN FOR A TRADE-MARK.

The Schedule referred to in these Letters Patent and making part of the same.

TO ALL WHOM IT MAY CONCERN:

Be it known that I, JOHN L. BERNECKER, of the city and county of Saint Louis, in the State of Missouri, have originated and designed a new Design for a Trade-Mark, of which the following is a full, clear, and exact description, reference being had to the annexed drawing, making a part of this specification.

My design consists of an eagle, with its wings spread, bearing upon its breast a shield, and holding in its talons two daggers crossed, in combination with the ornaments $\alpha\alpha'$ and the letters L and B, and the conjunctive sign &.

This design is intended to be used as an engraving or as a brand, and when used as the latter, the eagle, daggers, letters, and ornaments will have such breaks in them as may be necessary to give the requisite strength to the stencil or other plate by which the impression is made.

What I claim as my invention, and desire to secure by Letters Patent, is—

The design for a trade-mark substantially as shown and described.
